UNITED STATES PATENT OFFICE.

WILLIAM H. SMYTH, OF BERKELEY, CALIFORNIA.

ORE-ROASTING FURNACE.

SPECIFICATION forming part of Letters Patent No. 761,049, dated May 24, 1904.

Application filed March 12, 1901. Serial No. 50,868. (No model.)

To all whom it may concern:

Be it known that I, WILLIAM H. SMYTH, a citizen of the United States, residing at Berkeley, in the county of Alameda and State of California, have invented certain new and useful Improvements in Ore-Roasting Furnaces; and I do hereby declare the following to be a full, clear, and exact description of the same.

This invention relates to ore-roasting furnaces, and has for its object a simpler, cheaper, and more efficient form of furnace than those at present employed.

It also has for its object to provide means in an ore-roasting furnace whereby the rabble carrying and operating mechanism is carried entirely outside the furnace, and thus protected from the heat and destructive gases of the furnace.

Heretofore in ore-roasting furnaces difficulty has been experienced in providing for the driving of the rabbles within the furnace by means of connections extending into the furnace through open slots, either from the exterior of the furnace or from longitudinal chambers formed in the furnace, owing to the difficulty of maintaining the sides of such slots in proper relation one to the other and to the rabble-tracks. This is due to the peculiar nature of the furnace construction itself and the excessive duty demanded from such structures under the adverse condition of high temperatures. In furnaces having a slot in their sides opening to the exterior difficulty is experienced in supporting the furnace roof or arch. Attempts have been made to avoid this difficulty by providing a slotted wall or partition within the furnace proper; but this construction has the inherent disadvantage of the mechanical difficulty of supporting and maintaining the upper half of such slotted wall, besides the other disadvantage of the heated and corrosive fumes having practically free access to such corridors or chambers within the furnace. These difficulties have been partly met and overcome by slotting the hearth of the furnace longitudinally and carrying the rabble-supporting mechanism within a tunnel underneath the furnace. Difficulty has, however, been experienced in this class of furnace in maintaining the slot in operative condition, owing

to the closing together of the sides of the slot. Another difficulty experienced is the practically free access of cold air through the slot, causing a loss of heat, and consequent expense. This difficulty of maintaining the slot, with other mechanical difficulties, has heretofore precluded the employment of superimposed slotted furnaces.

One of the objects of the present invention is to provide for and remedy the first-mentioned difficulty; also, to provide an automatic slot-closing device which, while permitting of the free passage of the rabble-support, will close the slot and exclude the cold air and prevent the outflow of heated gases; also, to provide a construction which permits of ready access to the rabble-carriers and slot; also, to provide suitable construction whereby the rabble-carrying devices, adapted to be employed in the slotted-hearth type of furnace may be employed in a double or multiple hearth furnace. These objects are accomplished by the devices illustrated in the accompanying drawings, in which—

Figure 1 is a transverse sectional elevation of a single-hearth furnace. Fig. 2 is a transverse sectional elevation of a double-hearth furnace. Fig. 3 is a longitudinal sectional elevation of Fig. 1. Fig. 4 is a detail, on somewhat larger scale, showing the slot-closer. Fig. 5 is a sectional elevation of a multiple-slotted-hearth furnace. Fig. 6 is a detail, on still larger scale than Fig. 4, of the slot-closer, showing a plan view of the same. Fig. 7 is a side elevation of Fig. 6. Fig. 8 is a sectional plan view of a double slotted-hearth furnace, the hearths being side by side. Fig. 9 is an elevation of a double-hearth furnace, the hearths being superimposed. Fig. 10 is a section of one of the slot-closing plates or gates on a large scale. Fig. 11 is a plan view of a portion of a furnace. Fig. 12 is a cross-section of Fig. 11.

Referring to the drawings, I preferably construct this furnace with a metallic frame or skeleton upon which the brickwork of the furnace is built wholly or in part. This metallic framework or skeleton consists, preferably, as shown in the drawings, of a series of frames which transversely surround and

tie the furnace structure together, portions of the frame forming legs or supports which raise the furnace proper from the ground, as shown in Figs. 1, 2, 3, 5, and 9.

5 Referring to the construction shown in Fig. 1 or single-hearth construction, 1 is a furnace having a hearth 2, provided with a slot 3. The hearth 2, as shown in Fig. 3, is supported upon a series of arches 4, resting upon supports, transverse beams, or girders 5, which, if beams, are in turn supported upon suitable piers or columns 6. Upon the arch-supporting girders 5 is located track 7 for the rabble-carriage 8, which may be of any suitable 10 form. It preferably consists of a truck having four wheels, with the upright 9 passing through the slot 3 into the furnace to carry a suitable rabble-bar 10, to which rabbles 11 are attached by any of the ordinary methods. A chain, band, or rope 12, which is preferably endless, is attached to the rabble-supporting carriage 8 to cause its travel by suitable connection with a source of power. I provide a slot-closer 13, consisting, preferably, of flexible metal plates, which may be disposed scalewise, one overlapping the other along each side of the slot, touching and opposing each other along the line of the slot.

I do not deem it necessary to describe at 30 length the construction or arrangement of the heating fire-boxes 14 or flues of the furnace, as these may be of the ordinary forms and within the knowledge of mechanics skilled in this art and not specifically involved in this invention. Any suitable means for closing the furnace exit and entrances may be employed, such as are indicated at 21, Fig. 8.

So far as concerns the single-hearth furnace both folds of the endless band may travel 40 in either a horizontal plane or in a vertical plane, as may be deemed expedient by the constructor or may best serve the convenience of the location of the furnace. A single-hearth furnace with both folds of the cable 45 in a horizontal plane is illustrated in Figs. 11 and 12. With a double-deck furnace, however, I prefer to employ, as being the most economical of room, an endless band, both folds of which travel in the same vertical 50 plane. In this class of furnace only the lower hearth is slotted, the slot in the upper furnace being in the roof, and tracks supported on cross-ties support the inverted rabble, as shown in Figs. 2 and 9. The two parts of the 55 roof of the furnace may be supported in any simple manner. In the present instance I have shown them in Fig. 2 as consisting of projections 15 from the side walls in the form of half-arches provided with longitudinal 60 plates or girders 16, supported at intervals by brackets 17, suitably secured to cross-beams 18, forming a part of the metallic skeleton of the furnace. In this case of course the rabbles would be double, extending on 65 both sides of the rabble-bar, the tracks for

the rabble-carriages beyond the furnace curving upward and forming a continuation into the upper furnace, as shown in Fig. 9, thus guiding the rabble-carriages, with their rabble-supporting bars, from the lower to the 70 upper slot, and consequently the rabbles from the lower to the upper hearth. In this form I preferably employ a single pulley in the bight of the band to transfer the rabbles from one hearth to another. This pulley is 75 provided with one or more notches to accommodate the rabbles in passing around it, as shown in Fig. 9. Owing, however, to the method I employ of supporting the hearth by arches resting upon transverse beams, a double, triple, or multiple hearth furnace can readily be constructed by superimposing single furnaces, as shown in Fig. 1, but little room being wasted by this construction, as the piers shown in Fig. 1, would not necessarily 80 be employed between the superimposed furnaces, as shown in Figs. 2 and 9. That portion of the hearth which overhangs the tracks may be supported upon a plate or beam 19, which is in turn supported by brackets or 85 vertical members 20 from the cross-beams 5, which form a portion of the skeleton or metallic frame of the furnace.

When a multiple-hearth furnace is employed 90 consisting of superimposed furnaces and also furnaces side by side, I prefer to employ the slotted-hearth furnace with unslotted roof, as shown in Fig. 5, in which case the tracks for supporting the rabble-carriage curve laterally from one furnace to its next neighbor on 95 the same plane, as shown in Fig. 8. Thus the rabble-support on the rabble-carriage travels from the slot of one furnace into the slot of the adjacent furnace on the same horizontal plane and the rabbles carried thereby from 100 one hearth to the adjacent hearth on the same plane.

By the construction hereinbefore described 105 it will be seen that the rabble-carrying mechanism is at all times open and accessible to inspection and repair. The arrangement of the two portions of the multiple furnace, as shown, bring about very desirable features of economy in that the travel of the rabbles during the return half of their journey is utilized. The capacity of the furnace is thus practically doubled without any addition to the moving parts of the construction, at least so far as concerns the rabbling of the ore. The multiple arrangement also permits the discharge of ore from 110 the furnace at practically the same point at which it entered. It also permits in the same structure and with the same rabbling mechanism of different temperatures being maintained in the furnace or other different and independent treatment of ore on the rabbling-floors without interruption of a continuous process. Also by the arrangement and construction heretofore described the slot and 115 rails being in the same metallic structure and 120

practically independent of the brickwork are maintained in correct relative alinement, thus avoiding a serious practical difficulty and increasing the effective life of the carriage or 5 trucks and the rabbling mechanism generally.

Having now described this invention, what I claim as new, and desire to secure by Letters Patent, is—

1. A slotted-hearth furnace with rabble-actuating devices projecting through the slot and means for closing the slot. 10
2. A slotted-hearth furnace with rabble-actuating devices projecting through the slot and laterally-swinging plates or gates adapted to 15 close the slot.
3. A slotted-hearth furnace with rabble-actuating devices projecting through the slot and laterally-swinging plates or gates adapted to close the slot, the ends of which swing trans- 20 versely across the slot.
4. A slotted-hearth furnace with rabble-actuating devices projecting through the slot and means adapted to close the slot consisting of overlapping plates. 25
5. A slotted-hearth furnace with rabble-actuating devices projecting through the slot and means adapted to close the slot consisting of overlapping flexible plates. 30
6. In an ore-roasting furnace, a slotted 35 hearth and means adapted to support the same above the surface of the ground consisting of arches and transverse beams, the arches resting upon the beams, and columns adapted to support said beams, and means, attached to said beams, adapted to maintain the alinement of the slot.
7. A device consisting of superimposed ore-roasting furnaces having a slotted lower hearth and a slotted roof to the upper furnace. 40
8. In a device for roasting ores, a furnace-chamber having a slot intermediate of its sides and plates or gates to the slot adapted to swing transversely thereof, and a traveling rabble device adapted to pass through the slot. 45
9. In an ore-roasting furnace, a slotted hearth supported upon arches and means adapted to close the slot. 50
10. In an ore-roasting furnace, a slotted hearth supported upon arches and means for closing the slot consisting of overlapping plates. 55
11. In an ore-roasting furnace, a slotted hearth supported upon arches and means adapted to close the slot consisting of flexible overlapping plates. 60
12. A furnace for roasting ores comprising a plurality of superimposed slotted-hearth furnaces, rabbles adapted to travel above the hearths to stir the ore thereon, traveling bands adapted to effect the travel of the rabbles or stirrers therein, the parallel stretches of which travel in substantially the same vertical plane and means for closing the slots. 65
13. A furnace for roasting ores comprising a plurality of superimposed slotted-hearth furnaces, rabbles adapted to travel above the hearths to stir the ore thereon, traveling bands adapted to effect the travel of the rabbles or stirrers therein, the parallel stretches of which travel in substantially the same vertical plane and means for closing the slots. 70

naces, rabbles adapted to travel above the hearths to stir the ore thereon, traveling bands adapted to effect the travel of the rabbles or stirrers therein, the parallel stretches of which travel in substantially the same vertical plane and means for closing the slots consisting of overlapping plates. 75

14. A furnace for roasting ores comprising a plurality of superimposed slotted-hearth furnaces, rabbles adapted to travel above the hearths to stir the ore thereon, traveling bands adapted to effect the travel of the rabbles or stirrers therein, the parallel stretches of which travel in substantially the same vertical plane and means for closing the slots consisting of flexible overlapping plates. 80

15. A device consisting of superimposed ore-roasting furnaces having a slotted lower hearth and a slotted roof to the superimposed furnace and means adapted to close the slots. 85

16. A device consisting of superimposed ore-roasting furnaces having a slotted lower hearth and a slotted roof to the superimposed hearths and means adapted to close the slots consisting of overlapping plates. 90

17. A device consisting of superimposed ore-roasting furnaces having a slotted lower hearth and a slotted roof to the superimposed furnace and means adapted to close the slots consisting of overlapping flexible plates. 95

18. An ore-roasting furnace comprising a plurality of hearths one above the other, each provided with a roof, one of the hearths and one of the roofs being each provided with a slot and rabble devices adapted to project through said slots, and means adapted to transfer said devices from one slot to the other. 100

19. An ore-roasting furnace comprising a plurality of hearths one above the other, each provided with a roof, one of the hearths and one of the roofs being slotted longitudinally and means adapted to close the slots. 105

20. An ore-roasting furnace comprising a plurality of hearths one above the other, each provided with a roof, one of the hearths and one of the roofs being slotted longitudinally and means adapted to close the slots consisting of overlapping plates. 110

21. An ore-roasting furnace comprising a plurality of hearths one above the other, each provided with a roof, one of the hearths and one of the roofs being slotted longitudinally and means adapted to close the slots consisting of flexible overlapping plates. 115

22. An ore-roasting furnace having a plurality of superimposed hearths, each having a slot substantially central of the width of the furnace with rabble-actuating devices projecting through said slots and means for transferring the rabble-actuating devices from one slot to another and means adapted to close said slots. 120

23. An ore-roasting furnace having a plurality of superimposed hearths, each having a slot substantially central of the width of the 125

furnace with rabble-actuating devices projecting through said slots and means for transferring the rabble-actuating devices from one slot to another and means adapted to close said slots consisting of overlapping plates.

24. An ore-roasting furnace having a plurality of superimposed hearths, each having a slot substantially central of the width of the furnace with rabble-actuating devices projecting through said slots and means for transferring the rabble-actuating devices from one slot to another and means adapted to close said slot consisting of flexible overlapping plates.

25. A multiplicity of slotted-hearth ore-roasting furnaces with rabble-actuating devices projecting through the slots and means for transferring said devices from one slot to another and means for closing the slots.

26. A multiplicity of slotted-hearth ore-roasting furnaces with rabble-actuating devices projecting through the slots and means for transferring said devices from one slot to another and means for closing the slots consisting of overlapping plates.

27. A plurality of slotted-hearth ore-roasting furnaces with rabble-actuating devices projecting through the slots, means adapted to transfer said devices from one slot to another and means adapted to close the slots consisting of overlapping flexible plates.

28. An ore-roasting furnace having a plurality of ore-roasting chambers provided with alternate slotted roofs and slotted hearths, rabbles or stirrers therein and means adapted to operate the rabbles or stirrers.

29. An ore-roasting furnace having a plurality of ore-roasting chambers provided with alternate slotted roofs and slotted hearths, rabbles or stirrers therein and means adapted to operate the rabbles or stirrers and means for closing the slots.

30. An ore-roasting furnace having a plurality of ore-roasting chambers provided with alternate slotted roofs and slotted hearths, rabbles or stirrers therein and means adapted to operate the rabbles or stirrers and means adapted to close the slots consisting of overlapping plates.

31. An ore-roasting furnace having a plurality of ore-roasting chambers provided with alternate slotted roofs and slotted hearths, rabbles or stirrers therein and means adapted to operate the rabbles or stirrers and means adapted to close the slots consisting of flexible overlapping plates.

32. A roasting-furnace comprising a hearth resting upon supports to permit free circulation of air beneath the floor of said hearth, a longitudinal slot in said hearth and means for closing the slot.

33. An ore-roasting furnace comprising a hearth elevated above the surface of the ground whereby an unconfined air-space beneath the floor of the hearth is provided, a lon-

gitudinally-disposed slot in said floor, a rabbling mechanism within the furnace, a carrier outside the furnace and an arm extending through the slot and connecting the carrier and rabbling mechanism.

34. An ore-roasting furnace comprising a hearth elevated above the surface of the ground, whereby an unconfined air-space beneath the floor of the hearth is provided, a longitudinally-disposed slot in said floor, a rabbling mechanism within the furnace, a carrier outside the furnace, an arm extending through the slot and connecting the carrier and rabbling mechanism and gates in the slot so arranged as to give way to the passing arm and automatically resume their normal position after the arm passes.

35. In a device for roasting ores, a furnace formed of brick or the like and a metallic frame or skeleton transversely tying the brick structure, and having legs or columns which raise the brick structure above the ground, said frame having transverse members beneath the furnace at intervals in the length of the furnace and arches between and supported by the transverse members supporting the hearth.

36. In an ore-roasting furnace, a hearth or floor divided longitudinally into two sections, slightly separated to form a slot, a metallic frame or skeleton tying the furnace, and transverse bearing members of the metallic frame adapted to support the hearth-sections.

37. In an ore-roasting furnace having rabbles, a hearth longitudinally slotted intermediate of its sides, traveling means projecting through the slot adapted to effect the travel of the rabbles and means adapted to reduce the width of the slot consisting of plates or the like lying across the slot in the path of the rabble-moving means and attached by one edge at one side of the slot, so arranged that the free edge is moved transversely across the slot by the traveling rabble-moving means.

38. An ore-roasting furnace comprising a roasting-chamber and hearth, a longitudinally-disposed slot in the hearth, a rabble mechanism in the furnace, a carrier outside the roasting-chamber, an arm extending through the slot connecting the rabbles with the carrier and gates in the slot so arranged as to give way to the passing arm and automatically resume their normal position after the arm has passed.

39. In a device for roasting ores, a furnace-chamber constructed of brick or the like and having a slot intermediate of its sides, rabbling devices adapted to pass into and through said furnace, tracks for the rabbling devices, and a metallic skeleton or frame suitably arranged to form the support and attachment for the rabble-tracks and slot independently of the brick structure, whereby the tracks and slot are maintained in alignment.

40. In a device for roasting ores, a furnace-

chamber constructed of brick or the like having a hearth slotted intermediate of its sides, rabbling devices adapted to pass into and through said furnace, tracks for the rabbling devices, and a metallic skeleton or frame suitably arranged to form the support and attachment for the rabble-tracks and slot independ-

ently of the brick structure, whereby the tracks and slot are maintained in alinement.

WILLIAM H. SMYTH.
